SCREEN BAR

Ostap Danyluke, Philadelphia, Pa., assignor to
Pennsylvania Crusher Company, Philadelphia,
Pa., a corporation of New York

Application December 28, 1950, Serial No. 203,145

4 Claims. (Cl. 241—88)

1

This invention relates to screen bars for crushing machines and pulverizers having a rotor with crushing members and more particularly, is directed to the configuration of the walls of the slots between the screen bars of such machines.

The object of the invention is to provide screen bars with slots between the bars that are self-clearing and do not become choked with crushed material.

Another object of this invention is to provide a screen bar that is more durable and resistant to the abrasion of the crushed material.

A still further object of the invention is to provide a screen bar that produces a more uniformly sized material.

Other and further objects and advantages of the invention will appear from the following descriptions taken in connection with the drawings, in which

Fig. 1 is a sectional view of the machine; and Fig. 2 is a fragmentary view of a screen bar.

A ring type pulverizer embodying the invention is shown in Fig. 1 and comprises an outer casing 11, the cage 12 and rotor 13 with ring hammers 14. The rotor is mounted on a drive shaft 16 that turns the rotor in a counter-clockwise direction. The ring hammers 14 are connected to the rotor by pins 17, 18 positioned in pairs around the periphery of the rotor. On rotation the ring hammers extend outwardly as shown in Fig. 1 and sweep in close proximity to the breaker plate 19 and screen bars 21 and screen section 22 of the cage 12. The material to be crushed is dropped into the pulverizer through the delivery chute opening 23 and is initially crushed against the breaker plate 19 and then further broken against the screen bars 21 and screen section 22 by the rotating ring hammers 14. The broken pieces pass out of the machine through the slots 20 between the screen bars 21 and slots 24 of the screen section 22. The unbreakable material is carried upwardly and thrown into the tramp iron pocket 25 through the opening 30.

The top of the outer casing 11 comprises sheets of metal 26 mounted on beams 27 and has a delivery chute opening 23 above the rotor and offset from the center so that the material drops between the breaker plate 19 and the rotor 13 through the opening 30.

2

and into the path of the ring hammers 14. The breaker plate 19, screen bars 21 and screen section 22 of the cage 12 extend longitudinally across the machine from one side of the machine to the other. Both ends of the machine are the same and have a cradle 28 pivotally supported at its upper end on a shaft 29 and adjustably supported at the lower end by the adjusting mechanism 31. The adjusting mechanism 31 is mounted on the rotatable shaft 32 supported by the end walls 33 of the casing 11. The breaker plate 19 is mounted on the upper end of the cradle 28 and extends substantially vertical from the lower edge of the opening 23 to below the horizontal centerline through the rotor 13.

The screen bars 21 are mounted in the lower curve portion from a point just below the horizontal centerline through the rotor 13. These bars extend parallel to the shaft 16 and transverse to the direction of movement of the ring hammers 14. The ends of the bars are seated on the curved surface 34 of the cradle 28 and are tightly held between the lower end surface 35 of the breaker plate 19 and the cross member 36 interconnecting the lower ends of the cradles. The lower end surface 35 of the breaker plate 19 positions the upper bar 37 adjacent to the end of the breaker plate 19. The clamp 38 presses the upper end surfaces 39 of the bars 21 to hold the screen bars on the cradle 28. The clamp 38 is tightly fastened to the cradle 28 in a conventional manner.

The bars 21 are properly spaced by the webs 41 at the ends of the bar and by the webs 42 at uniformly spaced points along the bar forming the slots 20 transverse to the direction of motion of the hammers 14. In the embodiment shown the webs of the first four bars are shorter than the webs of the last four bars positioning the first four bars closer together and forming narrower slots. The trailing webs of the last four bars are longer spacing the bars half again as far apart and forming wider slots. Other size spacings and combinations of sizes may be used depending upon the material to be fractured and the desired resulting material.

The intermediate webs 42 are recessed below the inner and outer ends of the bars. The end webs are even with the surface 39. At the lower end of the cradle the webs of the end bar 44

engages the cross member 36. The cross member 36 is rigidly fastened at each end to the cradles 28.

The adjusting mechanism 31 comprises a crank 46 mounted on the rotatable shaft 32, a link 49 connected at one end to the crank 46 by the pin 48, and at the other end it is connected to the cradle by the pin 47. The space between the rotating hammers 14 and the screen bars 21 is varied by the adjusting mechanism 31 pivoting cradle 28 on the shaft 29. The space between the hammers and the screen bars is normally fixed and is only changed as the bars are worn or the desired size of the crushed material is changed.

In Figs. 1 and 2 each bar 21 has the same cross-sectional shape. The front or leading surface 52 is preferably plane and extends from the inner surface to the outer surface of the bar and forms with the inner surface a leading edge 53 having an acute angle. The leading surface 52 is at an angle to the radial lines extending through the center of the shaft 16 of the rotor 13. A radial line 63 is indicated passing between two bars. The other side of the screen bar has an inner trailing surface 54, and an outer exit surface 55, formed at an angle to each other. The inner trailing surface 54 extends from the inner surface of the bar to a point intermediate to the bar and is substantially parallel to the leading surface 52. The outer exit surface 55 is at an angle to the inner trailing surface 54 and the leading surface 52 tapering the outer portion of the bar to provide for an outwardly widening slot portion 56 between the bars.

The inner slot portion 57 defined by the leading surface and the inner trailing surface tilts to face the approaching hammers 14. The inner trailing surface 54 is preferably but not necessarily parallel to the leading surface 52 of the succeeding bar. These two latter surfaces should tilt in generally the same direction. The outer exit surface 55 breaks from this tilt widening the space between the bars.

The crushed material is continuously passing through the slots 20 and enters from several different directions. Some pieces pass directly through the inner slot portion 57, other pieces enter at an angle and bounce off the leading wall. The inner slot portion is approximately as wide as it is deep. The outer diverging portion 56 permits the pieces to leave the inner slot portion at different angles and does not attempt to constrict the flow from the slot to any particular directions.

The pieces clear freely through the outer slot portion permitting the pieces in the inner slot portion to flow freely outwardly without being blocked or conflicting with the preceding pieces. This cross-sectional shape of the bar that forms the desired shape slot may be used in other type machines such as hammermill type crushers and is not limited to the pulverizer type machine in which this type invention is shown and embodied.

The screen section 22 is a perforated plate or casting extending longitudinally across the machine and laterally from the end of the cradle 28 upwardly to the level of the rotor shaft 16. The plate is rigidly secured to the end walls 33 of the casing 11 to hold the screen section in position. The slots 24 extend through the plate and are transverse to the rotation of the hammers. This screen section provides a supplemental crushing surface and screening area to take care 75 of the

of the material carried by the hammers past the screen bars 21.

The protective surfaces 58 and 60 protect the casing 11 against material carried around by the rotor and thrown against the upper wall of the casing 11. The protective plate 59 is provided extending along the wall of the delivery chute 15 facing the hammers 14 to absorb the impact of any entering material that is given an upward blow throwing it back up into the chute. The side liners 62 are also extended along the side walls of the machine parallel to the rotation of the hammers and extend upwardly into the chute.

It is thus seen that the material entering 15 through the delivery chute 15 positioned above the rotor and between the center of the rotor and the upper end of the breaker plate 19 drops between the downwardly descending rotor and the breaker plate 19 and the hammers 14. It is carried downwardly by the moving hammers and further fractured between the inner surfaces of the screen bars and the hammers. The broken pieces fall and are thrown or knocked through slots 20. Slots 20 are so shaped so that the broken pieces will either pass directly through a slot or reflect off the walls into the divergent portion and will not be constricted by the depth of the slots.

I claim:

1. In a crusher having a rotor with hammers 30 for crushing frangible material introduced into said crusher, a cage having screen bars with walls transverse to the movement of said hammers forming a material passing slot between a set of bars, each bar comprising a plane surface impact receiving wall facing in the direction of approach of said hammers and extending the full depth of said slot, a hammer facing wall forming an edge at an acute angle with said impact wall and a trailing surface wall having an inner portion substantially parallel to said impact wall and forming with the opposing impact wall an inner slot for passing the crushed material and an outer wall portion at a tapering angle with the impact wall to form an outer outwardly expanding exit slot with the opposing impact wall to disperse the crushed material leaving the inner slot.

2. In a crusher as claimed in claim 1 wherein 50 said bars have an inner crushing surface tangentially disposed in relation to the movement of said hammers forming the leading sharp edge with said impact wall against which said frangible material is crushed.

3. In a crusher as claimed in claim 1 wherein 55 said bars are spaced by end webs and intermediate webs transverse to the bars and having engaging surfaces substantially radial to the center of rotation of the rotor, said end webs having the inner and outer end surfaces even with the inner and outer surface of said bars and said intermediate webs having surfaces recessed from said inner and outer surfaces.

4. In a crusher having a rotor with impact members at the periphery thereof and a cage 65 having screen bars with slots therebetween transversely disposed to the direction of rotation of the impact members, each slot having a face set at an angle to the radial lines through the center of the rotor forming a long abrasion surface inclined outward in the direction of movement of the impact members and an opposite face having a first surface substantially parallel to said first face and providing a passage inclined to the 70 radial through the inner portion of the slot, and

a second surface at an angle to said first portion for divergently widening the slot outwardly to facilitate the discharge of the crushed material from said entrance passage.
